UNITED STATES PATENT OFFICE.

ROBERT KIRK BOYLE, OF BROOKLYN, NEW YORK, ASSIGNOR TO HIMSELF,
JAMES M. PRENDERGAST, OF BOSTON, MASSACHUSETTS, AND DANIEL
H. CRAIG, OF NEW YORK, N. Y.

TELEGRAPHY.

SPECIFICATION forming part of Letters Patent No. 309,126, dated December 9, 1884.

Application filed April 17, 1884. (No model.)

To all whom it may concern:

Be it known that I, ROBERT KIRK BOYLE, a subject of the Queen of Great Britain, residing at Brooklyn, in the county of Kings and State of New York, have invented new and useful Improvements in Telegraph Apparatus, of which the following is a specification.

This invention relates to a telegraph apparatus which is intended particularly for submarine cables, or for a system of telegraphing in which alternate positive and negative electric impulses are sent over the line.

The peculiar and novel construction of my apparatus is pointed out in the following specification and claims, and illustrated in the accompanying drawings, in which—

Figure 1 represents a side elevation. Fig. 2 is a sectional plan of a portion of the apparatus. Fig. 3 is a plan or top view, partly in section. Fig. 4 is a horizontal section in the plane x x , Fig. 1, on a larger scale than the previous figures. Fig. 5 is a face view of the pen and the means for supporting the same. Fig. 6 is a diagram illustrating the connection of the various parts.

Similar letters indicate corresponding parts.

In the drawings, the letter A designates a large electro-magnet, which is permanently charged with electricity from a strong local battery, B, Fig. 6.

Between the jaws A' A² of the electro-magnet extend vertical wires 10 and 11, which are supported by the following means:

On the under surface of the base C, (which is of wood or other bad conductor of electricity,) are secured two brackets, a b, in each of which is secured a stud, a' b', respectively, and on the stud a' is secured a wire, 10°, while on the stud b' is secured a wire, 11°. Each of these wires is provided with an insulating-section, 10² 11², respectively, and the upper ends of said wires are secured to axles c d, respectively, which turn freely in bearings formed on standards c' d', and which are provided with buttons c² d² and with tightening-nuts c³ d³. By turning the buttons c² d² in the proper direction the wires 10° 11° can be tightened, and when they have acquired the requisite tension the axles c d are locked by the

nuts c³ d³. The wires 10 and 11 are bent at 50 their upper and lower ends, and fastened to the wires 10° 11°, respectively, as shown in Figs. 1, 3, and 6, the bent portions of said wires being designated by 10² and 11², respectively.

From the wire 10 extends an arm, 12, and from the wire 11 extends an arm, 13. The outer end of the arm 12 is provided with a hook which engages with an eye formed at the outer end of an arm, 14, which extends 60 from a wire, 15. This wire passes loosely through holes in lugs e f, which extend from a bracket, g, in the upper end of which is secured a hair, h, from which the wire 15 is suspended. The lower end of the wire 15 dips 65 into mercury contained in a cup, i.

From the wire 15 extends a second arm, 16, beneath the arm 14, Figs. 1 and 4, between contact-points 17 18, which rise from the insulated head j of a slide, D. This slide is 70 guided in lugs k k, secured in one side of a block, E, of hard rubber or equivalent material, which is fastened on the base C. From the slide D extends a pin, l, into a slot formed in an arm, m, which extends from a spindle, o, which turns freely in its bearings, and round this spindle is wound a cord, p^o, extending from one end of a spring, p, so that when the spindle is free to follow the action of this spring the slotted arm m carries the slide D 80 outward; but when the spindle is turned so as to wind up this spring the slide D is carried inward.

On the spindle o is mounted a ratchet-wheel, q, which is subjected to the action of 85 a propelling-pawl, q', and of a stop-pawl, q², the latter serving to retain the ratchet-wheel q against the action of the spring p at the time the pawl q' is moved back. The propelling-pawl is L-shaped, and it is mounted on a pin, 90 q^o, secured in an arm, q², which is connected with a lever, F², the fulcrum of which is on a stud, q³, secured in the block E, and which carries the armature F' of an electro-magnet, F. The stop-pawl q² is made in the form of a spring 95 secured to an arm, r, which is connected to a lever, G², the fulcrum of which is on a stud, r^o, and which carries the armature G' of an

electro-magnet, G. The propelling-pawl is subjected to the action of a spring, s, which acts on a pin, s^o, projecting from the tail of said L-shaped propelling-pawl, and it is normally held in gear with the ratchet-wheel q by the action of this spring.

From the armature-lever G² extends an arm, r², which bears against the pin s^o, and from said lever G² extends another arm, r', which is intended to act on the stop-pawl q².

In the arm r is secured a secondary stop-pawl, q²⁰. Whenever the armature F' is attracted the pawl q' is drawn back, and when the armature is retracted the pawl q' propels the ratchet-wheel q in the direction of the arrow marked on it in Fig. 1. The slide D moves inwardly, and the cord p^o, connected with the spring p, is wound up on its spindle o by such movement of the armature-lever F', and by alternately magnetizing and demagnetizing the electro-magnet F several times in succession the slide D will be moved inward for any desired distance. When the armature G is attracted, both the propelling-pawl q' and the stop-pawl q² are thrown out of gear with the ratchet-wheel q, one by the arm r, which acts upon pin s^o, projecting from the downwardly-extending arm of the pawl q', and the other by the arm r', which acts directly upon the tip of the pawl q². The spindle o is then free to follow the action of or be controlled by the action of the spring p, and the slide D is carried outward; but this outward motion is checked by the secondary stop-pawl q²⁰, which is thrown into gear with the ratchet-wheel instantaneously after the pawls q' q² have been raised out of engagement, so that the outward motion of the slide D is limited, the ratchet-wheel q being permitted to revolve in the direction opposite to the arrow marked thereon only for one tooth. At the same time the break between the arm 16 and contact-point 17 does not take place at once, and the armature G' vibrates continuously until a complete break is made and the ratchet-wheel turns for several teeth. On the opposite side of the block E is situated the slide D* and two electro-magnets, which act upon the slide in the same manner in which the electro-magnets F G act upon the slide D.

In the head of the slide D* are secured two contact-points, 17* 18*, between which extends an arm, 16*, extending from a wire, 15*, which connects by an arm, 14*, with the arm 13, extending from the wire 11. The wire 15* dips into a mercury-cup, i*, all these parts being counterparts of the devices connected with the slide D and wire 10, so that they require no further description.

On the front or outer end of the slide D* is secured a short tube, t, and on the outer end of the slide D is secured a guide, t'. (Best seen in Fig. 5.)

P is the pen, which is made in the form of a siphon, its rear end being supported by the tube t and passing through this tube into the ink-well Q, while its shank passes through a

hole in the guide t' and is bent, so as to bring the tip of said pen to bear upon the strip of paper S, which is drawn over the support R by clock-work or other means generally used for this purpose. From this description it will be seen that when the slide D is moved the inner end of the pen P swivels in the tube t, and the tip of the pen follows the motion of the slide; but if the slide D* is moved, the pen turns in the guide t' and its tip moves in a direction opposite to that of the slide.

Above the block E are situated two relay-magnets, H I, Figs. 1 and 2, the armatures H* 80 I* of which are mounted on rock-shafts h^o i^o and extend through the centers of the magnets, being held in contact with dead-stops h⁶ i⁶, respectively, by the action of springs h⁷ i⁷. When the relay-magnets are vitalized, their 85 armatures are drawn up against the front stops, h⁸ i⁸.

I will now proceed to describe the operation of my apparatus with relation to Fig. 6. It must be remembered that the electric impulses sent through the cable W are alternately positive and negative. If an electric current of a given kind—say a positive current—passes from the cable through screw b' to wire 11, thence through standards d' c' and 95 wire 10° to wire 10, and through screw a' to ground, the wires 10 and 11 are repulsed by the jaws of the electro-magnet in the direction of the arrows 19 and 20, the arm 12 of wire 10 turns wire 15 and throws arm 16 against contact-point 17, a circuit is closed from local battery B* through wire 21, mercury-cup i, wire 15, arm 16, contact-point 17, wire 22, helix of electro-magnet G, and wires 23 24 back to battery B*, the electro-magnet G is vitalized, the armature G', Fig. 1, is attracted, the pawls q' q² are thrown out of gear with ratchet-wheel q, the spindle o follows the action of the spring p, and the slide D moves outward, and a short oblique mark is traced on the strip of paper. By a succeeding electrical impulse of the same kind a second mark is drawn on the strip of paper, so that by four positive impulses the letter "h" is produced, as shown in Fig. 4. By the movement of the slide D the contact-point 17 is drawn away from the arm 16, the circuit through electro-magnet G is broken, and the movement of the slide D is arrested. The current may press the wire 16 with so much force against the contact-point 17 (both said wires 120 being elastic) that it may require a movement of the ratchet-wheel of several teeth to move the slide sufficiently away to break contact between arm 16 and contact-point 17, and when the contact is broken the slide is at rest 125 until the current on the cable ceases. As soon as this takes place the wire 10 falls back to its normal position, the arm 16 is brought up against contact-point 18, a circuit is closed from battery B* through wire 21, mercury-cup i, wire 15, arm 16, contact-point 18, wire 26, helix of electro-magnet F, and wires 25 24 back to the battery, the armature F', Fig. 1, is attracted, and the ratchet-wheel q is turned 130

so as to wind up spring p and to move the slide D inward until the arm 16 ceases to be in contact with contact-point 18. In this position the slide is at rest, and by the inward movement of the slide the point of the pen has been carried back to the center line of the paper-strip. The movement imparted to the tip of the pen is increased by the movement of the slide D^* , which is in a direction opposite to that of the slide D . When the current coming from the cable is negative, the wires 10 and 11 are forced toward each other and the movements of the slides D D^* are reversed, so that by two negative impulses the letter "I" is traced upon the strip of paper, as indicated in Fig. 4. If there is no current in the cable, the pen P occupies a position over the center line of the strip of paper, and by positive electric impulses the pen is moved toward the left of the center line, Fig. 4, while by negative impulses it is moved toward the right.

The system of recording characters to represent letters or other arbitrary symbols will be sufficiently understood from the above description, since it is evident that different movements, dots, or spaces may be understood to represent any arbitrary symbols as agreed upon.

What I claim as new, and desire to secure by Letters Patent, is—

1. The combination, in a telegraph-instrument, of a permanently-charged electro-magnet having jaws A' and A^* , of the wire 10, stretched between said jaws and forming a continuation of the line or cable, the slide D , the pen or recording device connected with said slide, and mechanism, substantially as described, for operating the slide D or pen-carrier by the attraction or repulsion of wire 10, as herein set forth.

2. The combination, substantially as hereinbefore described, with the permanently-charged electro-magnet, of the wire 10, which forms a continuation of the line or cable, and which is stretched between the jaws of the electro-magnet, the arm 12, extending from said wire and acting on wire 15, the arm 16, extending from this wire, the contact-points 17 and 18, secured in the head of the slide D , and mechanism substantially such as herein

described, said mechanism being controlled by the position of the arm 16 in relation to the contact-points 17 and 18, and serving to impart motion to the slide D .

3. The combination, with the permanently-charged electro-magnet, of a wire, 10, which forms a continuation of the line or cable, and which is stretched between the jaws of the electro-magnet, the arm 12, extending from said wire and acting on wire 15, the arm 16, extending from this wire, the contact-points 17 and 18, secured in the head of the slide D , the spring-propelled spindle o , connected to the slide, the ratchet-wheel q , mounted on this spindle, the electro-magnets F G for controlling the motion of the spindle o and their connections, substantially as shown and described.

4. The combination, with the permanently-charged electro-magnet, of a wire, 10, which forms a continuation of the line or cable, and which is stretched between the jaws of the electro-magnet, the arm 12, extending from said wire, the suspended wire 15, the arm 16, extending from this wire, the contact-points 17 and 18, secured in the head of the slide D , the mercury-cup i , the spring-propelled spindle o , connected to the slide, the local battery B^* , the electro-magnets F G and their connections, substantially as shown and described.

5. The combination, with the permanently-charged electro-magnet, of two wires, 10 and 11, which form a continuation of the line or cable, and are stretched between the jaws of the electro-magnet, the arms 12 and 13, extending from said wires, two slides which carry the pen or recording device, and mechanism substantially such as herein described, said mechanism being actuated by the attraction and repulsion of the wires 10 and 11, and serving to impart motion to the slides.

In testimony whereof I have hereunto set my hand and seal in the presence of two subscribing witnesses.

ROBERT KIRK BOYLE. [L.S.]
